UNITED STATES PATENT OFFICE.

JOHN A. J. SHULTZ, OF ST. LOUIS, MISSOURI.

LEATHER STUFFING AND FULLING MACHINE.

SPECIFICATION forming part of Letters Patent No. 245,321, dated August 9, 1881.

Application filed January 18, 1881. (No model.)

To all whom it may concern:

Be it known that I, JOHN A. J. SHULTZ, of St. Louis, Missouri, have made a new and useful Improvement in Leather Stuffing and Fulling Machines, of which the following is a full, clear, and exact description, reference being had to the annexed drawings, making part of this specification, in which—

Figure 1 is a plan of the improved machine, 10 a portion of the stuffing-cylinder being broken away; Fig. 2, a side elevation; Fig. 3, an end elevation; Fig. 4, a section, taken on the line *xx* of Fig. 2; Fig. 5, a detail, being an elevation, looking in the direction of the arrow, of 15 Fig. 1, and showing the lever and parts immediately therewith connected, of the shifting mechanism, and Fig. 6 a cross-section taken on the line *y* of Fig. 1.

The same letters denote the same parts.

20 I have heretofore (May 16, 1876) patented an improvement in leather stuffing and fulling machines.

The present invention is an improvement upon the construction referred to, the improvement relating partly to the means for confining and cramping the leather in a longitudinal direction in the stuffing cylinder or trough during the stuffing operation, and partly to the mechanism employed in changing the 25 direction of the rotation of the cylinder-shaft.

Referring to the drawings, A represents the cylinder wherein the leather is stuffed, and B the cylinder-shaft to which the leather is fastened, and by means of which the leather is rotated and worked within the cylinder. These 35 parts—the cylinder and shaft—are, saving as modified by the cramping mechanism in question, substantially the same as in the original construction.

40 E E' represent followers movable longitudinally on the shaft B, being spaced sufficiently apart thereon to receive between them the leather that is attached to the shaft. The followers are connected together so as to properly 45 confine the leather longitudinally in the cylinder, the connections, however, being elastic, in order to yield and elongate and allow the followers to open whenever an unusual strain, as when the leather in its working becomes 50 unusually bunched or knotted, comes upon them, and to contract again and draw the fol-

lowers toward each other into their original positions as soon as the strain is relieved.

The connecting devices are shown at F F' at each side of the cylinder, and connecting 55 with the arms *e e*, with which the followers are furnished, and which project through or beyond the shell of the cylinder. The devices F F', more particularly described, are as follows: rods *ff'*, at their outer ends, are held 60 in the arms *e e*, and at their inner ends are respectively provided with, or made in the form of, the parts *f²f³*. The latter are respectively furnished with projections *f⁴f⁵*, which interlock similarly to a clutch. A bearing, *f⁶*, is attached to the ends of the projections *f⁴*, and a similar bearing, *f⁷*, to the ends of the projections *f⁵*. Springs *f⁸f⁹* are arranged between the bearings *f⁶f⁷*, and act to press the bearings apart, and in so doing to draw the followers together. 70 The bearings *f⁶f⁷* may be in the form of hand-wheels, as shown in Figs. 1, 2, 6, and the rods *ff'* are threaded, so as to screw into the parts *f²f³*. This last-described feature enables the 75 followers to be readily relatively adjusted, for by turning the hand-wheels and clutches upon the rods the devices F F' are elongated or shortened, as the case may be. For this purpose the threads upon the rods *ff'* run in opposite directions, and the rods, in their bearings in the arms *e e*, are squared to prevent 80 their being turned.

The improved mechanism for changing the direction of the rotation of the cylinder-shaft is as follows: As in the original construction, 85 a pulley, J, is arranged on a shaft, I, upon the inner end of which is a pinion, H, engaging with a gear, G, upon an extension of the shaft B. The gear G also engages with a pinion, K, that is attached to a shaft, L, which is threaded 90 at *l*. A nut, O, is upon this threaded portion *l*, and by the time the shaft B has made the proper number of revolutions in one direction the nut has been caused to travel on the shaft L sufficiently to move the lever Q, and thereby 95 the slide R. This shifts the driving-belt onto the pulley J''. The motion is then transmitted through the shaft S, (to which the pulley J'' is attached,) gear-wheels S' L', shaft L, and pinion K, to the gear G, causing the latter to 100 rotate in the opposite direction. The nut O now travels in the opposite direction until the

lever Q has been thrown over into its original position, when the operation is repeated, and so on.

To prevent the nut O from rotating with the shaft L the nut is provided with an arm, o, which travels in a guide, o', and to operate the lever Q the nut is furnished with an arm, o², which engages with the projections q q' upon or connected with the lever Q—that is, in moving in one direction the arm o² presses against the projection q, and in moving in the other direction it presses against the projection q'. The latter is connected with the slide R by means of the rod R'. The slide R has the usual arms, r r', for shifting the belt.

It will be seen that the shaft N'' of the original construction is dispensed with and the mechanism otherwise simplified.

I claim—

1. The combination of the cylinder A, followers E E', and connections F F', substantially as described.

2. The combination of the rods f f', parts f² f³, projections f⁴ f⁵, bearings f⁶ f⁷, and spring f⁸, substantially as described.

3. The combination of the parts f² f³, projections f⁴ f⁵, bearings f⁶ f⁷, and spring f⁸, substantially as described.

4. The combination of the hand-wheels f⁶ f⁷, rods f f', parts f² f³, projections f⁴ f⁵, spring f⁸, and arms e e, substantially as described.

5. The combination of the cylinder A and the followers E E', said followers being connected together by means of elastic connections.

6. The combination of the pulleys J J'', shafts I B L S, gears H G S' L' K, nut O, lever Q, and slide R, substantially as described.

JOHN A. J. SHULTZ.
